UNITED STATES PATENT OFFICE.

HARRY D. WYRE, OF ORRVILLE, OHIO.

CULVERT-PIPE.

1,052,198.

Specification of Letters Patent. Patented Feb. 4, 1913.

Application filed November 29, 1912. Serial No. 734,045.

To all whom it may concern:

Be it known that I, HARRY D. WYRE, a citizen of the United States, residing at Orrville, in the county of Wayne and State 5 of Ohio, have invented certain new and useful Improvements in Culvert-Pipes, of which the following is a specification.

The invention relates to metal culvert pipes of the character usually employed for 10 constructing sewers and other conduits; and the object of the improvement is to make the pipe in semi-cylindric sections for economy in casting, and to provide means for holding the sections against longitudinal or 15 lateral displacement when brought together to form a pipe section and by which the semi-cylindric sections can be held together by pins for transportation or handling.

A further object of the improvement is to 20 so shape the bell flange of the pipe and the holding means so that by removing the pins on one side, the upper section can be raised upon the opposite edge of the lower section as a fulcrum, to give access to the interior 25 of the pipe for cleaning and other purposes.

The objects of the improvement thus set forth in general terms are attained by the preferred embodiment of the invention 30 illustrated in the accompanying drawings, forming part hereof, in which:

Figure 1, is a side elevation of a full pipe section made of two semi-cylindric sections and held together by the improved holding 35 means; Fig. 2, a perspective view of one semi-cylindric section; Fig. 3, a cross section on line 3—3, Fig. 1; Fig. 4, a similar section showing the upper section opened from the lower section; Fig. 5, a side elevation of a pipe made with broken joints; and Fig. 6, a perspective view showing a pipe section with the upper half opened from the lower half.

Similar numerals refer to similar parts 45 throughout the drawings.

The semi-cylindric sections 1 of the pipe are all made alike, excepting that a half section 1^a must be used at each end of the series for making a pipe with staggered 50 joints. Each long semi-cylindric section is provided with the lateral rib 2 on each side edge, the annular rib 3 on the spigot end, and the intermediate ribs 4 around the side of the pipe, which ribs are provided for 55 strengthening the pipe and are preferably made with their edges in the same circum-

dential alinement; and for the purposes of the present invention, the lateral ribs 2 are preferably tapered from the body of the pipe to a comparatively thin edge. The bell flange 5 is provided on the other end of the section and is shaped to telescope freely over the spigot end of an adjoining section. 60

On one side edge of each long semi-cylindric section are provided two laterally disposed hooks 6, formed with the inner sides of their shanks extended substantially tangent to and beyond the edge of the lateral rib, and with a portion of their sockets outside the plane of the section edges; and on the other side edge of the section are provided two pairs of similar hooks 6^a, the hooks of each pair being spaced apart to be opposite the sides of the corresponding single hook 6, and each set of hooks being located in the middle of the respective end halves of the section, ignoring the length of the bell flange. 70

To form a full pipe section, two long semi-cylindric sections are placed together, 80 and it is evident that the single hooks on the one side of each section will enter between the corresponding pair of hooks on the abutting edge of the other section, as shown in Fig. 1; and it is evident when the sections are thus assembled, the abutment of the sides of the overlapping hooks will prevent a longitudinal displacement of the sections with reference to each other, and the abutment of the tangential shanks of 85 the hooks with the lateral ribs, will prevent a lateral displacement of the sections. With the hooks in this relation, it is evident that the pins 7 may be entered endwise into the opposing sockets formed by the several 90 overlapping hooks, by means of which the semi-cylindric sections will be held together. 95

It will be understood that the use of pins is not necessary to hold the sections together when the pipe is installed under the ground, 100 but are intended more particularly for holding the two sections together for transporting and handling the full sections of pipe. It is furthermore evident that it is unnecessary to remove the pins when the full sections are placed in the ground, for the reason that by making the pins out of wood, 105 which is the preferred material, they will readily shear, in event of an expansion of the pipe by frost, without injuring the holding hooks. 110

Each short semi-cylindric section 1^a is

similarly provided with a single hook 6 on one side edge and a pair of similar hooks 6^a on the other side edge, and it is evident that such a short section can be employed in conjunction with a series of long sections, for making a pipe with staggered joints, as shown in Fig. 5; and by this arrangement, it is furthermore evident that the hooks of each long section will overlap 10 with corresponding hooks in the two opposing long sections, thereby holding or interlocking the several longitudinally abutted sections together.

The bell flanges 5 are beveled outwardly 15 at each side edge of the semi-cylindric section, and it is evident that by reason of the peculiar shape of the hook shanks set forth herein, the removal of the pins from one side of a full pipe section, permits the upper 20 half thereof to be rotated upward on the opposite edge of the lower half as a fulcrum, as shown in Figs. 4 and 6, to give access to the inside of the pipe for cleaning and other purposes.

25 I claim:

1. A culvert pipe made of semi-cylindric sections with one or more lateral hooks on one side edge and corresponding pairs of hooks on the other side edge, whereby cor- 30 responding hooks of adjoining sections will

overlap each other, each hook having its shank extended substantially tangent to the edge of the section and a portion of its socket outside the plane of the edges thereof.

2. A culvert pipe made of semi-cylindric 35 sections having tapered ribs on each side edge, with one or more lateral hooks on one edge and corresponding pairs of hooks on the other edge, whereby corresponding hooks of adjoining sections will overlap 40 each other, each hook having its shank substantially tangent to the edge of the lateral rib and a portion of its socket outside the plane of the section edges.

3. A culvert pipe made of semi-cylindric 45 sections having a bell flange on one end and tapered ribs on each side edge, with one or more lateral hooks on one edge and corresponding pairs of hooks on the other edge, whereby corresponding hooks of adjoining 50 sections will overlap each other, each hook having its shank substantially tangent to the edge of the lateral rib and a portion of its socket outside the plane of its section edges; the bell flange being beveled at the 55 section edges.

HARRY D. WYRE.
